UNITED STATES PATENT OFFICE

HARRY D. BETZ, OF KANSAS CITY, MISSOURI

DESIGN FOR A HOUSING OF AIR-COOLING UNIT

Application filed January 27, 1930. Serial No. 34,310. Term of patent 7 years.

To all whom it may concern:

Be it known that I, HARRY D. BETZ, a citizen of the United States, residing at Kansas City, in the county of Jackson and State of Missouri, have invented a new, original, and ornamental Design for Housing of Air-Cooling Unit, of which the following is a specification, reference being had to the ac-

companying drawing, forming part thereof. The figure is a perspective view of a housing of air cooling unit, showing my new design.

I claim:

The ornamental design for a housing of air cooling unit, as shown.

HARRY D. BETZ.
